2,526,021

APPARATUS FOR DISCHARGING VISCOS
LIQUIDS IN A WELL

Wilford B. Fultz, Graham, Tex.

Application June 18, 1945, Serial No. 600,187

1 Claim. (CL 166—19)

1

This invention relates to improvements in apparatus for discharging viscous liquids at and near the bottom of a well, and more particularly to the discharging of viscous liquids at a regulated discharge rate in the well as the bailer is moved upward, thus presenting no opportunity for the viscous liquid to "set" about the outside of the dumping bailer for the liquid and to be withdrawn therewith.

The dumping of liquids from a dumping bailer into the bottom of a well has long been practiced, but the comparatively recent use of viscous liquids or cellulose plastics to seal off certain formations, and their behavior, has presented new problems. This invention has been designed to overcome the problems and difficulties peculiar to the dumping of viscous liquids or cellulose plastics into a well and removing the dumping bailer therefrom.

The primary object of this invention is to provide for discharging viscous liquids in a well in regulated amounts as the dumping bailer is being withdrawn from the well.

Another object of this invention is to provide for discharging viscous liquids in the bore hole of a well in such manner that they will be discharged at the desired place but will not adhere to the dumping bailer and be withdrawn thereby from the well.

Still another object of this invention is to provide for dumping viscous liquids in the bore hole of a well at the place and rate desired and without waste of the liquid or adherence of the liquid to the apparatus which might render it inoperative inefficient.

Another object of this invention is to discharge liquid plastic in the bore hole of a well for the purpose of sealing off certain formations, for example, to prevent intrusion of water during the drilling of an oil well, and without sealing the dumping apparatus in the well as the liquid sets.

The invention is shown in different embodiments in the accompanying drawings in which:

Fig. 1 is a vertical section through a deep well with parts broken away and in section to show the dumping bailer discharging viscous liquids at a point near the bottom of the well;

Fig. 2 is a longitudinal section through one form of dumping bailer, illustrating the discharge orifices in open position;

Fig. 3 is a cross section therethrough, on the line 3—3 of Fig. 2;

Fig. 4 is a similar view on the line 4—4 of Fig. 2;

Fig. 5 is a fragmentary section of the lower portion of the dumping bailer, showing the discharge orifices in closed position;

2

Fig. 6 is a similar view, partly in elevation, through a modified form of the invention;

Fig. 7 is a cross section on the line 7—7 of Fig. 6;

Fig. 8 is a similar view on the line 8—8 of Fig. 6;

Fig. 9 is a similar view on the line 9—9 of Fig. 6; and

Fig. 10 is a longitudinal section through still another modified form of the invention.

The invention is shown in connection with a deep well 1 having a casing 2 therein. The well 1 extends downwardly in the earth formation, such as oil-containing formation, and projects below the lower end of the casing 2.

A dumping bailer, generally designated as 3, is shown suspended by a cable 4, in position in the lower part of the well 1 with viscous liquid or liquid plastic P therein. Fig. 1 illustrates how the liquid plastic passes from the lower end of the dumping bailer, the dumping bailer initially containing the liquid plastic therein. The dumping bailer 3 may be of different forms, as desired. I have shown several forms in the drawings for purpose of illustration.

In the form of dumping bailer 3 shown in Figs. 2 to 5, a long tubular body is adapted to form a receptacle for containing the viscous liquid P for discharge therefrom. The body is formed of sections 5, 6, 7 and 8 interconnected in rigid relation, having screw-threaded connection with each other.

One or more intermediate sections may be used according to the length and capacity desired, two of which are shown at 6 and 7. The bailer should contain sufficient plastic to fill the bottom cavity of the well. The upper section 5 has a bail 9 fixed thereto for suspension of the bailer by the cable 4.

The lower section 8 is partially closed at its lower end with a guide sleeve 10, and is provided also with discharge openings 11 in different sides thereof. A sleeve valve 12 controls the openings 11, having openings 13 in position to register therewith.

The sleeve valve 12 is fixed, by welding or otherwise, to a guide rod 14 extending vertically through the tubular body and down through the guide sleeve 10, with a foot 15 on the lower end thereof. The guide rod 14 has a spring latch 16 fixed to a side thereof in position to engage a seat 17 in the guide sleeve 10, to hold the rod in its elevated position, as shown in Fig. 2. An orifice 18 in the sleeve 10 adjacent the seat 17 provides access to the latch 16 to release the latter from the seat 17. The upward movement

of the valve 12 is limited by a shoulder 19 at the lower end of the section 7.

A piston 20 is mounted in the tubular body in position to bear on the column of viscous liquid therein, and is sleeved over the guide rod 14. The piston 20 preferably carries a cup 21 in position to urge the viscous plastic toward the bottom of the dumping bailer.

The piston 20 is held at a point near the top of the dump bailer by a latch 22. The latch 22 is substantially of bell-crank shape and is pivotally mounted at 23 on a bracket 24 secured to the upper section 5. One arm of the bell-crank latch 22 overlies the upper end of the guide rod 14, while the other arm thereof is in position to engage a lug 25 which is secured to the top of piston 20. The latch 22 is held in engagement with lug 25 by a torsion spring 26.

In the process of using the device as shown in Figs. 2 to 5, the upper section 5 of the tubular body is removed and one or more sections 6, 7, are connected to the lower section 8 sufficient to accommodate the desired quantity of viscous liquid. With the valve 12 closed, as shown in Fig. 5, the tubular body is filled with viscous plastic. The upper section 5 is then secured in place with the piston 20 above the body of liquid.

The dumping bailer is then lowered into the well as shown in Fig. 1, until the foot 15 on the lower end of the rod 14 touches the bottom of the well, as shown in dotted lines in Fig. 1. This will move the rod 14 upward and cause the bell-crank latch 22 to move from the position shown in dotted lines to the position shown in full lines in Fig. 2. As the rod 14 moves upward with the valve 12 the latter will engage the shoulder 19 and will cause ports 11 and 13 to be moved into registry.

When the piston 20 is released by the latch 22, the weight thereof will force the viscous plastic down in the body and out through the ports 11 and 13, into the lower portion of the well. Then the dumping bailer is moved upward immediately from the position shown in dotted lines in Fig. 1, at a predetermined rate of travel, and the viscous liquid will flow outward into the bottom of the well with only the lower end of the dumping bailer extending into the discharged plastic.

It will be appreciated that by maintaining the discharge ports substantially at the upper level of the discharged body of viscous plastic in the well, air bubbles will be prevented from forming, as would be the case if the plastic material were dumped from a higher elevation. However, with the dumping bailer moving upward at a regulated rate, with only the discharge ports and the lower extremity of the bailer below the surface of the viscous plastic, water or other liquid in the well, of lighter specific gravity, will be floated upward above the plastic and thus be prevented from mixing therewith. With only the lower end of the dumping bailer protruding into the viscous plastic only a very small amount would adhere to the bailer as it empties and is moved upward.

The weight of the piston 20 should be sufficiently heavy to cause the viscous liquid to be discharged through the open ports 11 and 13. By calculation or experimentation the time interval required for the piston to travel downward to the bottom of the bailer and discharge all the viscous plastic as the bailer moves upward away from the body of plastic in the well can be determined readily. With the rate of travel of both the piston and the bailer regulated so that the

bailer is emptied just as the lower end thereof reaches the top of the discharged plastic, it can be appreciated readily that the flow of the plastic upward around the bailer is prevented and that the bailer is withdrawn from the plastic before the same can set therearound.

After the viscous plastic has been allowed to harden or "set" at the point where it has been deposited in the well in order to seal off a particular formation, such as a caving formation, which will harden and prevent caving, a hole may be drilled therethrough, if desired, so that drilling or other operations may be continued, but leaving the hardened plastic adhering to the walls of the well in an annular ring to seal off the desired formation. The usual practice is to seal off the water by letting the plastic harden in the lower portion of the well to hold the water back. The plastic penetrates the formation and as it hardens it expands to form a positive seal therewith and is bonded thereto by adherence to the plastic within the formation.

Any or all of the modifications of the invention are applicable to the use or uses of liquid plastic in the well.

One modified form of the bailer is shown in Figs. 6 to 9, in which a tubular shell, generally designated by the numeral 33, has an upper section 35, one or more intermediate sections 36, a swaged section 37, and a lower section 38 threaded onto the swaged section 37. An annular shoulder 39 on the lower section 38 holds a frangible disc 40 against the bottom of a sealing gasket 41 to close the lower end of the swaged section 37 so as to retain the viscous plastic therein.

Ports 42 are formed in the lower portion of the section 38 to permit the viscous plastic to be discharged therethrough when frangible disc 40 is broken. An axial rod 43 passes through the lower end of the tubular section 38 and in alignment to break the frangible disc 40 on the upward movement of the rod 43 against the tension of a spring 44. A pin 45 retains the rod 43 in the desired spaced relation from the frangible disc 40, limiting the downward movement of the rod.

An eye-stem 46 is mounted in the upper portion of the tubular section 35, and has a head 47 adapted to engage a bell-crank latch 48, which latch is held in engagement with a hook 49 by a torsion spring 50. The bell-crank latch 48 is pivotally mounted on a pin 51, between ears 52 at one side of the tubular section 35. The hook 49 is provided on a weighted piston 53, which preferably has a cup 54 secured to the lower end thereof and adapted to fit the inner wall of the tubular sections 35, 36.

The modification of the invention as shown in Figs. 6 to 9 utilizes the same principle as that described above. However, the method of releasing the viscous plastic is by lowering the dumping bailer to the bottom of the well by a cable or other suitable means attached to the eye-stem 46, until the axial rod 43 seats on the bottom of the well. This causes the rod 43 to move upward relatively against tension of the spring 44 and to break the frangible disc 40 which normally seals the lower end of the dumping bailer and retains the viscous plastic therein until such frangible disc is broken by the relative upward movement of the rod 43 when it strikes the bottom of the well.

When the weight of the dumping bailer is relieved from the cable, the stem 46, to which the cable is attached, will move downward relatively

to trip bell crank latch 48 which will release the piston 53. The piston then moves downward in the dumping bailer to start the discharge of the viscous plastic through ports 42 as the bailer is moved upward in a manner substantially as described above.

A further modification of the dumping bailer is shown in Fig. 10, in which a tubular body, generally designated as 63, has an upper section 65, with a bail 69 thereon, one or more intermediate sections 66 and a lower section 68. The lower section 68 has an axial rod 74 protruding from the lower end thereof for engagement with the bottom of the well. The lower end of the section 68 is reduced to form a guide for the rod. A spring latch 76, similar to the latch shown in Fig. 2, engages a seat 77' to retain the valve 72 attached to the rod 74, in open position. Ports 71 in the section 68 are adapted to register with holes 71 in a sleeve valve 72, when the valve is in raised position.

A piston 80 is adapted to be fitted within the tubular member 63 and has a cup 71 seated on the column of liquid, thereby preventing the movement of the piston 80 downward until the ports 71 and holes 73 register and permit the outward flow of the viscous plastic from the tubular body 63 into the wall. Since the cup 81 is in snug fitting relation with the inner diameter of the tubular body 63, it will be prevented from moving downward unless the viscous plastic is being discharged, and it will also allow the weight of the piston to force the liquid out.

In the form of the invention shown in Fig. 10, the dumping bailer operates in a manner similar to that shown in Fig. 2 and described above, except that the piston 80 is allowed to rest or float on top of the viscous plastic contained in the tubular body. The dumping bailer is then lowered into the well until the axial rod 74 strikes the bottom of the well. This will cause the latch 76 to engage the seat 77' and hold the valve in raised position with ports 71 and 73 in registry.

The piston 80 then moves downward forcing the viscous plastic outward through said ports, and the dumping bailer is simultaneously raised at such rate that as the viscous plastic fills the lower portion of the well, the ports 71, 73 will be maintained substantially at the top level of said discharging plastic or with the bottom of the bailer only slightly submerged therein. This method of dumping the viscous plastic into the bottom of the well will allow it to flow in place without mix-

ing with any water that may be present in the well and without air bubbles becoming entrained therein.

After the viscous liquid has been dumped in the well, and the entire contents of the bailer discharged, the bailer 63 is withdrawn and a rod or tool passed through the hole 78 opposite spring 76 to release the spring from its seat 77', so that the valve may be moved downward to the position shown in Fig. 10. The bailer is then ready for re-use.

It will be evident that the dumping bailer should be raised at a predetermined rate, as described above. This may be accomplished by any suitable hoisting mechanism attached to the line 4, and so controlled by the operator as to move the bailer upward at the same rate that the liquid level rises in the well, keeping the discharge orifices at the liquid level. No particular form of hoisting mechanism is required for this purpose.

I claim:

In an apparatus for dumping viscous liquid at a point near the bottom of a well, the combination of a tubular body adapted to be lowered in the well, a frangible seal closing the lower end of said tubular body, a rod passing through the lower portion of said tubular body below said seal and movable therein, said rod being in position to move upwardly to break said frangible seal upon contact of said rod with the bottom of the well, a piston disposed within said tubular body above the viscous liquid in the body, a latch on the body initially holding the piston stationary in the upper end of said tubular body means movably mounted in the upper end of said tubular body and movable to engage and release said latch to release said piston after said tubular body reaches the bottom of said well.

WILFORD B. FULTZ.
